SCREW INSERT

James E. Quigley, Fanwood, N. J., assignor to
Western Electric Company, Incorporated, New
York, N. Y., a corporation of New York

Application March 30, 1946, Serial No. 658,478

1 Claim. (Cl. 151—33)

1

This invention relates to inserts, particularly of the internally threaded type for attachment to thin sheet material for use in mounting articles upon the sheet material by the use of screws.

In the manufacture of various types of electrical apparatus, thin sheet material, such as aluminum, is desirable to serve as panels for electrical units, the only difficulty arising, however, in the mounting of such units on the material or panel. To construct the panel of a sheet material sufficiently thick to accommodate the mounting screws for the electrical units, it would be necessary to more than double the thickness of the material. Then too, material such as aluminum is too soft to assure permanent and satisfactory mounting of electrical units by the aid of screws.

An object of the invention is to provide an insert which is simple in structure and easily attachable to thin sheet material to provide adequate bearing for the thread of a mounting screw.

The invention comprises an insert including a body with a boss integral therewith and receivable in an aperture of a thin sheet of material. The boss and the adjacent portion of the body have a threaded aperture therein to receive a mounting screw through the aid of which an article may be secured to the sheet of material. The insert is secured to the material by a rivet-like portion integral with the body, receivable in another aperture of the material spaced from the first mentioned aperture and having a recess in its outer end forming an annular flange which may be bent outwardly to rigidly secure the body to the material.

Other objects and advantages will be apparent from the following detailed description when considered in conjunction with the following accompanying drawings, wherein

Fig. 1 is an enlarged sectional view of the insert prior to the forming of the threads therein;

Fig. 2 is a top plan view of a panel illustrating pairs of the inserts;

Fig. 3 is a front elevational view of the panel shown in Fig. 2, this view being taken substantially along the line 3—3 of Fig. 2, and

Fig. 4 is an enlarged fragmentary sectional view taken along the line 4—4 of Fig. 2.

Referring now to the drawing, attention is first directed to Fig. 1 which illustrates the insert as including a body 10 substantially pear shaped in general contour and having an annular integral boss 11. An aperture 12 extends through the body and the boss 11 and is subsequently provided with threads 14 (Fig. 4). A rivet portion

2

15 formed integral with the smaller end of the body 10 has a recess 16 in its outer end to form annular flange 17.

Although the sheet of material or panel 18 appears to be of considerable thickness in Fig. 4, attention is directed to Figs. 2 and 3 which illustrate the full size of the insert and the material 18 in reality is quite thin. An opening 20 is formed in the material for the boss 11 and a smaller opening 21 is formed at a spaced position from the opening 20 in the material for the rivet 15. After the threads 14 are formed in the insert, the insert is placed with the boss 11 and the rivet 15 disposed in their respective openings, after which outer portions of the flange 17 are spun or otherwise formed outwardly to rivet the insert in place as illustrated in Fig. 4.

When a suitable number of inserts have been mounted at selected positions on the panel, articles or units 22 and 23 may be secured in place by the aid of mounting screws 24.

A portion of the insert functions as a nut for the mounting screw providing material of suitable thickness for the threads of the screw and also material of a given hardness to provide a satisfactory mounting for the article or unit. The rivet portion of the insert functions first in securing the insert to the material at a position spaced sufficiently far from the main opening in the material for the mounting screw so that the material is not weakened and also serves to hold the nut portion against rotation during the driving of the screw in place or the removal of the screw. Another advantage in spacing the rivet portion from the boss lies in the fact that the necessary tool may be used in forming the rivet during the securing of the insert in place without causing damage to the threads 14.

Although specific improvements of the invention have been shown and described, it will be understood that they are but illustrative and that various modifications may be made therein without departing from the scope and spirit of this invention as defined by the appended claim.

45 What is claimed is:

A screw support for a thin metal member to provide adequate bearing for the thread of a screw to secure an article to the front surface of the member, the support comprising a thin metal member with spaced openings therethrough, an element thicker than the member and having a body of sufficient size to cover the back surface of the member between the openings and for given distances beyond the openings, a boss short of 50 the edge of the body, integral therewith, fitting

slidably in one of the openings of the member, having its outer end terminating at or short of the front surface of the member and having a threaded aperture therein for the screw extending through the body to urge the body toward the back surface while securing the article to the front surface, a rivet integral with the body short of its edge, receivable in the other opening of the member and having its outer end swaged outwardly and terminating in the plane of the front surface or short thereof thus constituting the sole means for securing the body to the member prior to securing of the article in place.

JAMES E. QUIGLEY.
